LYSANDER HILL AND ADELAIDE R. HILL, OF ALEXANDRIA, VIRGINIA.

Letters Patent No. 73,892, dated January 28, 1868.

IMPROVED CRADLE.

The Schedule referred to in these Letters Patent and making part of the same.

TO ALL WHOM IT MAY CONCERN:

Be it known that we, LYSANDER HILL and ADELAIDE R. HILL, both of the city and county of Alexandria, in the State of Virginia, have invented a new and useful Improved Cradle; and we do hereby declare the following to be a full, clear, and exact description thereof, sufficient to enable one skilled in the art to which our invention appertains to construct and use the same, reference being had to the accompanying drawings forming a part of this specification, in which—

Figure 1 is a side elevation.

Figure 2 is a side elevation.

Figure 3 is a bottom view.

In the drawings, similar letters of reference indicate corresponding parts.

In this invention the cradle has a longitudinal vibrating motion, its body being kept at all times perfectly horizontal. The body and head of the child are thus prevented from rolling from side to side, and all the injurious effects of the old-fashioned cradle are avoided. In addition to this, the cradle is here so constructed that it can be instantly changed from a cradle to a child's wagon, at pleasure.

For a long time physicians have been aware that the old-fashioned cradle for rocking children is productive of very injurious effects upon the child, and of late years so strong has been this conviction in the popular mind that the cradle, as a means for quieting the child and lulling him to sleep, seems gradually going out of use. The injury results chiefly from the fact that in rocking, the child's head rolls from side to side, twisting its neck first one way and then the other. Such a motion is not only permanently injurious to children of a tender age, but so far as it tends to cause their heads to roll in the manner described, is at the same time annoying to them, retarding rather than facilitating the approach of sleep. It is to avoid all these injurious effects that we have invented the improved cradle which is the subject of this application, and in which the rolling motion is avoided as herein explained.

In the drawings, A A represent the body of the cradle, supported upon two axles, G G, in the manner of a wagon, or, more properly, in the manner of a railroad-car, inasmuch as the axles are designed to turn in their bearings. The axles are provided at each of their extremities with a rocker, B, firmly fixed to them, and a wheel, C, revolving loosely on them like a common wagon-wheel, the rocker and wheel being kept from wearing against each other by means of a collar on one or the other, or a washer or shoulder on the axle between them. The radius of the wheel is less than the shortest distance from the axle to the tread of the rocker, so that when the cradle rests on the rockers, as seen in fig. 1, the wheels do not touch the floor. When the axles and rockers are turned bottom up, however, the cradle rests upon the wheels, as seen in fig. 2, and may be hauled round from place to place by the child, with perfect ease, answering every purpose of a toy wagon. When thus turned up out of the way, the rockers may be fastened in that position by any suitable means. Perhaps the simplest and best adjustment will be that shown in fig. 3, in which D is a bar, pivoted at d, and swinging on the pivot, as shown in black and red lines. The axles, at points on a line with the pivot d, are made square, and the ends of the bar D, when the latter is brought against the axles, as shown in black lines, prevent the rockers from moving from the position shown in fig. 2. When the bar D is in the position shown in red lines in fig. 3, the axles and rockers are free to move. The black lines show the position of the bar D when the cradle rests on the wheels, and the red lines show its position when the cradle rests on the rockers. Any other means of fastening the rockers in position may be used, however, that will answer the purpose as well. On the front end of the cradle is a loop or link, e, in which to fasten a cord or tongue, if it should be desired, when the instrument is employed as a wagon.

One object in this invention is to entirely do away with the rolling motion of the cradle, and to substitute instead of it a longitudinal reciprocating motion, so controlled that the body of the cradle is caused to remain at all times in a horizontal position. In producing such a motion we do not wish to limit ourselves to the particular means above described, but may, in lieu of it, employ a device in which the body of the cradle is suspended by cords or arms at or near each end, so as to swing longitudinally upon the cords or arms, while always maintaining a horizontal position. When thus constructed, the cords or arms may be attached to rollers, or other

wise made adjustable, so that by shortening or raising them the height of the cradle from the floor can be regulated, as well as the length of the arc through which the body of the cradle will swing, and so that at the same time, the rapidity with which the cradle will swing back and forth can be adjusted at pleasure.

A cradle constructed as shown in the drawings, and working upon two axles, supported by four rockers, has, besides the improved motion, several important advantages over the old form of cradle, among which may be mentioned the fact that it cannot be upset, and the child thrown upon the floor, by rocking it violently; neither will it tip down when the child attempts to sit or stand up in it, or climb over its side, thereby giving him a fall, and, perhaps, a serious injury, but under all circumstances it keeps its horizontal position, and is perfectly safe for the child to climb over in any manner.

If it is desired that the motion of the cradle should be increased to a greater extent than is practicable when the axle bears directly in the rockers, as above described, it may be made to bear in the top of perpendicular arms or standards, projecting upwards from the rockers at the centre of their upper edges, and when such standards are used, the axles may be dispensed with altogether, and the top of the standard may be pivoted to the sides of the cradle, so that it will swing back and forth between them, just as it now swings on the rockers, only with an increased motion.

It is perhaps unnecessary to add that the journals, or the whole axle, may be made of iron, brass, or any other metal, composition, or substance, which will diminish friction, and give the device an easy, uniform motion back and forth. If desired, the axles or the front and rear rockers may be connected by a rod.

The invention may be applied to any form of cradle or crib.

Having thus described our invention, what we claim as new, and desire to secure by Letters Patent, is—

1. A cradle, so constructed and operating that it vibrates longitudinally, the body of the cradle always keeping a horizontal position, substantially as and for the purpose set forth.

2. In connection with a cradle, operating as above described, we claim the axles G G, arranged transversely under the body of the cradle, and having rockers, B B B, attached to their extremities, and operating in the manner and for the purposes substantially as specified.

3. We claim the combination of the cradle-body A with the rockers B B and wheels C C, when the parts are so constructed and connected that the device may be adjusted to serve either as a cradle or a wagon, substantially in the manner described.

LYSANDER HILL,
ADELAIDE R. HILL.
